(57) **CLAIM**

The ornamental design for a capsule, as shown and described.

DESCRIPTION

FIG. 1 illustrates a top front perspective view of the capsule showing my new design;

FIG. 2 illustrates a bottom front perspective view thereof;

FIG. 3 illustrates a left side elevation view thereof;

FIG. 4 illustrates a right side elevation view thereof;

FIG. 5 illustrates a front elevation view thereof;

FIG. 6 illustrates a rear elevation view thereof;

FIG. 7 illustrates a top view thereof;

FIG. 8 illustrates a bottom view thereof;

FIG. 9 illustrates a top front perspective view of the capsule showing my new design in another embodiment;

FIG. 10 illustrates a bottom front perspective view of the capsule of FIG. 9;

FIG. 11 illustrates a left side elevation view of the capsule of FIG. 9;

FIG. 12 illustrates a right side elevation view of the capsule of FIG. 9;

FIG. 13 illustrates a front elevation view of the capsule of FIG. 9;

FIG. 14 illustrates a rear elevation view of the capsule of FIG. 9;

FIG. 15 illustrates a top view of the capsule of FIG. 9; and,

FIG. 16 illustrates a bottom view of the capsule of FIG. 9.
